SUPERSATURATED OIL SOLUTIONS OF
STEROID HORMONES

21 Claims. (Cl. 167—74)

1

The present invention relates to injectable hormone preparations of androgenic, estrogenic and other types.

It is the general object of the invention to provide injectable liquid preparations having unusually high concentrations of the androgenic, estrogenic or other hormones.

It is a further object of the invention to provide injectable liquid hormone preparations in which the solubility of the hormone has been increased by the presence in the liquid of another steroid compound which is non-toxic in character and which itself may or may not have hormone activity.

It is a still further object of the invention to provide injectable hormone preparations in which an increased concentration of the hormone in the injectable liquid is made possible by the use of substances which are similar chemically to the hormone compound and are easily tolerated by the body, and without the aid of substances which are foreign to body metabolism.

The extremely low solubility of the steroid hormones, including the androgenic and estrogenic hormones, in the liquids usually employed for injection has given rise to various efforts and expedients for introducing increased concentrations of the hormones into the body. Resort has most commonly been had to the use of emulsions, pellet implantation, aqueous suspensions, and solvent mixtures, but none of these has proved entirely satisfactory. The amount of hormone that can be suspended in an emulsion is quite limited, and the use of emulsions is therefore not satisfactory when large concentrations are desired. Emulsions are unstable and difficult to sterilize without the use of stabilizing agents of unknown or questionable physiological properties, particularly as these stabilizing agents usually consist of substances which are quite foreign to body chemistry. Pellet implantation permits the introduction of a high concentration of hormone, but this mode of administration has the serious disadvantage that it requires a minor surgical operation. Moreover, cases have been reported wherein pellet implantation has resulted in hormone rejection by the tissue. In an aqueous suspension, the hormone is in the solid condition and its absorption into the blood stream by way of the aqueous medium is slow and the rate of absorption is difficult to control. Dosage control is also difficult in such case, and difficulty is also experienced occasionally in injecting such preparations owing to the coagulation or agglomeration of the particles and clogging of the hypodermic needles.

2

Many efforts have been made to find improved solvents for hormones which are non-toxic in character, but without any noteworthy success. At the present time the best solvents used in conjunction with sesame oil seem to be benzyl benzoate and benzyl alcohol, but their use has been very limited because they are exceedingly irritating when employed in amounts sufficient to increase materially the concentration of the hormones.

We have found that the concentration of a steroid hormone in an injectable liquid can be very considerably increased by the simple expedient of adding to the liquid another non-toxic steroid compound. The steroid compound can be completely neutral physiologically or it may have a mild or even a high physiological action which does not interfere with that of the hormone, and it may even have a hormone activity similar to that of the hormone to be injected. The increase in solubility effected by our steroid solubilizer can be as much as 150 to 400% and even more. This increased solubility was quite unexpected and appears to be contrary to the "common ion" theory of solubility in the case of ionizing substances; for in such case it is known that ionizing compounds like salts have a reduced solubility in a liquid which already has in solution a compound having an ion in common with the salt. While steroid hormones are different substances from ionizable salts, nevertheless it was to be expected that a steroid compound would have a lower, rather than a greater, solubility in a solvent already containing another steroid compound.

Among the steroid compounds which either are without physiological effect at the concentrations necessary for improving the solubility of the administered hormone, or are of such low physiological action that at the indicated concentration their activity can be neglected, are cholesterol, sitosterol, dehydroandrosterone, dehydroandrosterone acetate, pregnandiol, pregnandiol acetate and other esters, desoxycholic acid, wool fat alcohols, isoandrosterone and isoandrosterone acetate, benzoate, and other esters, and dehydroisoandrosterone and its acetate, benzoate and other esters. Numerous other steroid compounds fulfill the requirements of substantial physiological inertness, particularly at low concentrations, and can be used in preparing the compositions of our invention.

In addition to the androgenic and estrogenic hormones above referred to, also other hormones of steroid character can be utilized as the administered hormone whose concentration in the

injectable medium is to be increased. Among these may be mentioned the various adrenal hormones and related steroid hormones, together with steroid substances of intermediate character which are apparently utilized by the body in building up various hormones. Included among these are cortisone and other steroid hormones having an anti-arthritis activity, pregnenolone, etc.

Among the sex hormones of which solutions of high potency can be prepared in accordance with the present invention are testosterone esters, particularly the propionate, progesterone, methyl androstendiol and pregnenolone and its esters, like the acetate and benzoate. With progesterone, dehydroisoandrosterone acetate gives a preparation containing a high concentration of the former, while pregnenolone and a pregnenolone ester, like the acetate, can be used together. Testosterone and testosterone propionate yield a preparation in which the solubility of the testosterone propionate in, for example, sesame oil, is increased by over 150%. With methyl androstendiol there can be employed cholesterol and numerous other inert steroids. The injectable liquid is preferably a vegetable oil like sesame, peanut and corn oils. These oils may be used singly or in mixtures. While the solubilities of the different steroids in these different oils will vary, there is in all cases a very substantial increase in the solubility of the administered hormone due to the presence of the other steroid.

The invention will be further described by way of the following examples which are, however, presented only by way of illustration and not as indicating the limits of the invention.

Example I

50 cc. of sesame oil were saturated with testosterone, the resulting concentration of the steroid in the oil being 9 mg./cc. This solution was then saturated with testosterone propionate. The resulting solution contained, in addition to the 9 mg./cc. of testosterone, also 215 mg./cc. of the propionate. Comparing this solubility of testosterone propionate with the 82 mg./cc. of the ester which is contained in a saturated solution thereof in sesame oil free from other steroids (see Example II), it will be seen that the presence of the small proportion of unesterified testosterone increased the solubility of the ester by over 150%.

Example II

50 cc. of sesame oil were saturated with testosterone propionate. The resulting solution contained 82 mg. of the ester per cc. of the oil. This solution was then saturated with testosterone, and 46 mg./cc. went into solution. It will thus be seen that the prior saturation of the oil with testosterone propionate increased the solubility of the testosterone by over 400%, since the solubility of testosterone in sesame oil (Example I) is only 9 mg./cc.

The above examples show that it is not the specific character of the steroid, but the fact that it is taken up in a solvent already containing another steroid in solution, that accounts for the increase in solubility of the first steroid; and we have found this principle to be of wide application with the greatest variety of steroid combinations.

It will be apparent that it will not always be necessary to saturate the solution containing the solubilizing steroid with the steroid to be administered, since an adequate concentration of

the latter may be achieved below saturation in such solution, but above the normal saturation concentration in the absence of the steroid solubilizing agent. In certain cases it may not even be necessary to use the solubilizing agent at saturation to produce a supersaturated solution of the hormone to be administered (with reference to the saturation concentration of such hormone in the injectable liquid alone).

The above examples show that to attain maximum concentration of the administered hormone, the solubilizing steroid should be dissolved first in the liquid injection medium, and the hormone only thereafter; but where the hormone is not to be used at maximum concentration, more or less simultaneous solution of the two steroids will give satisfactory results.

We claim:

1. An injectable hormone composition comprising a solution of a steroid hormone in an injectable oil containing another, added non-toxic steroid compound in solution, the concentration of the hormone being greater than its saturation concentration in such oil in the absence of the added steroid compound.
2. An injectable hormone composition comprising a solution of an androgenic steroid hormone in an injectable oil containing another, added non-toxic steroid compound in solution, the concentration of the hormone being greater than its saturation concentration in such oil in the absence of the added steroid compound.
3. An injectable hormone composition comprising a solution of an estrogenic steroid hormone in an injectable oil containing another, added non-toxic steroid compound in solution, the concentration of the hormone being greater than its saturation concentration in such oil in the absence of the added steroid compound.
4. A composition as defined in claim 1, wherein the added steroid compound is in substantially saturated solution in the oil.
5. A composition as defined in claim 1, wherein the steroid hormone is in substantially saturated solution in the solution of the added steroid compound.
6. A composition as defined in claim 1, wherein the injectable oil is a vegetable oil.
7. A composition as defined in claim 1, wherein the injectable oil is sesame oil.
8. A composition as defined in claim 1, wherein the added non-toxic steroid compound has hormone properties similar to that of the steroid hormone.
9. A composition as defined in claim 1, wherein the hormone is a testosterone ester and the added steroid compound is testosterone.
10. A composition as defined in claim 9, wherein the testosterone ester is the propionate.
11. A composition as defined in claim 1, wherein the hormone is a testosterone ester and the added steroid compound is testosterone, and wherein the injectable oil is sesame oil.
12. An injectable hormone composition comprising a solution of progesterone in an injectable oil containing another, added non-toxic steroid compound in solution, the concentration of progesterone being greater than its saturation concentration in such oil in the absence of the added steroid compound.
13. An injectable hormone composition comprising a solution of methyl androstendiol in an injectable oil containing cholesterol in solution, the concentration of methyl androstendiol being

greater than its saturation concentration in such oil in the absence of the added cholesterol.

14. An injectable hormone composition comprising a solution of a pregnenolone ester in an injectable oil containing added pregnenolone in solution, the concentration of pregnenolone ester being greater than its saturation concentration in such oil in the absence of the added pregnenolone.

15. An injectable hormone composition comprising a substantially saturated solution of pregnenolone acetate in an injectable oil which is substantially saturated with added pregnenolone.

16. An injectable androgenic hormone composition comprising a solution of a male hormone having a high androgenic activity in an injectable oil which is substantially saturated with an added steroid compound having a low androgenic activity, the concentration of the male hormone being greater than its saturation concentration in such oil in the absence of the said added steroid compound.

17. An injectable estrogenic hormone composition comprising a solution of a steroid hormone having a high estrogenic activity in an injectable oil which is substantially saturated with an added steroid compound of relatively low estrogenic activity, the concentration of the estrogenic hormone being greater than its saturation concentration in such oil in the absence of the said added steroid compound.

18. A composition as defined in claim 1, wherein in both the added steroid hormone and the steroid compound are present in substantially saturation concentration.

19. Process for the preparation of injectable hormone compositions which comprises substantially saturating an injectable oil with an added non-toxic steroid compound, then dissolving in the solution a quantity of a steroid hormone in

excess of its saturation concentration in the absence of the added steroid compound.

20. Process for the preparation of injectable hormone compositions which comprises substantially saturating an injectable oil with an added non-toxic steroid having no or only minor hormone activity, and thereafter saturating the solution with a steroid hormone.

21. Process for the preparation of injectable steroid compositions which comprises substantially saturating an injectable vegetable oil with testosterone, and thereafter substantially saturating the solution with testosterone propionate.
